PAPER WINDING MACHINE

Jacob F. Albright, Bastrop, La.

Application December 7, 1934, Serial No. 756,528

11 Claims. (Cl. 287—52)

The present invention relates to paper winding mechanism such as is used for winding paper made on a paper making machine.

More particularly the invention relates to a detachable collar means adapted to be readily applied to the shaft of a paper winding machine and clamped thereon to hold the paper sheet being wound against lateral slippage, and to this end the invention aims generally to improve existing devices.

In order that the invention may be better understood, reference is made to the accompanying drawing and following detailed description of one embodiment of the invention which has proved to be highly successful in practice.

In the drawing—

Fig. 1 is a side elevation of the improved collar applied to a shaft of a paper winding machine;

Fig. 2 is a horizontal sectional view taken on the line 2—2 of Fig. 1;

Fig. 3 is a vertical sectional view taken on the line 3—3 of Fig. 2;

Fig. 4 is a view similar to Fig. 3 illustrating the position of the parts as the collar is ready to be placed upon the shaft;

Fig. 5 is a vertical sectional view taken on the line 5—5 of Fig. 3; and

Fig. 6 is a horizontal sectional view taken on the line 6—6 of Fig. 3.

The embodiment of the invention illustrated in the drawing comprises a housing 10, one side of which is bifurcated to provide an open throat 11 of sufficient width to enable the housing to be slipped over the shaft 12 of a paper winding machine. The housing 10 preferably comprises spaced side frames 13 and 13^a and a central semi-hub portion 14 communicating with the throat 11 and in which a portion of the shaft 12 is positioned when the collar is in its operative position on the shaft. The housing 10 is advantageously recessed to receive a peripheral cover plate 15 which may be secured in place by any suitable means, as for example, screws 16, and one side of said housing may be recessed to receive a closure plate 17 held in place by screws 18.

The hub portion 14 is suitably constructed to receive toothed blocks or dogs 19, and preferably the hub portion 14 is formed with a dovetail groove 20 and the blocks 19 are similarly shaped so that the latter may be inserted from the side and held firmly in fixed position. The blocks or dogs 19, are formed with teeth 21 obliquely cut on the face of the block so that upon relative rotation between the shaft 12 and the block 19 the block and housing will be moved toward and

in tight engagement with the end of the roll. The teeth of both upper and lower blocks 19 engage the surface of the shaft 12 on the same side of the vertical axes of the shaft as illustrated in Fig. 1.

Additional gripping means for clamping the housing 10 on the shaft and preventing accidental removing therefrom are provided, and preferably comprise a pair of movable blocks or dogs 22 engageable with the shaft on the opposite side of its vertical axis from the blocks 19, so that when the collar is in its operative position on the shaft, the shaft is embraced by a plurality of toothed blocks engaging its surface in opposite sides of any diametrical axis, the spacing between any two blocks being of less distance than the diameter of the shaft. To this end the housing 10 is formed with inclined guideways 23 to receive movable dogs 22 having teeth 24 cut in angularly disposed faces thereof.

Means are provided for exerting a resilient tension upon the dogs 22 to normally force and hold them in engagement with the shaft 12, and preferably the means is such that a uniform tension is exerted upon opposed dogs 22. As herein disclosed a pair of leaf springs 25 may be fixedly mounted in the housing 10 in any conventional manner, said springs having their free ends extending forwardly and engaging in seats 26 in the locking dogs 22 so as normally to exert a tension to move the dogs inwardly into engagement with the shaft.

Each of the dogs or pawls 22 is provided with a recess or seat 27 to receive the end of a locking bar or bolt 28 slidably mounted in the housing and reciprocable toward and from the seat 27. The locking bar or bolt is formed intermediate its ends with a recess or seat such as at 28^a to receive a trigger 29, one end of which is journalled in a recess as at 30 in the housing 10, and the other end is free to be moved into and out of the throat 11. Advantageously there are two triggers 29 provided which may be under the tension of a suitable spring 29^a. When the dogs or pawls 22 are in inoperative position, and are retracted in the guideways 23, the locking bar or bolt 28 engages the seat 27 of its dog 22 and holds the dog in inoperative position. In this position the free end of each trigger 29 is positioned within the throat as shown in Fig. 4. The collar is thus ready to be applied to the shaft.

As the collar is applied to the shaft of the machine the throat portion is slipped over the shaft and as it is moved into proper position, the shaft engages the free ends of the triggers 29 swinging

them rearwardly out of engagement with the seat 21, permitting the dogs 22 to be moved inwardly into engagement with and embracing the shaft 12.

5 The housing sides may be formed with slots 31 and the dogs 22 with sockets 32 for the reception of pins or the like of any suitable tool whereby the dogs may be retracted in their guideways 23 when it is desired to remove the collar from the 10 shaft.

15 The principal advantages of my invention reside in the provision of a collar for the purpose described that may be readily applied to and snapped upon a shaft while in motion so as not to require stopping the machine and dismantling of the shaft bearing in order to apply the collar. Furthermore the use of slideable or reciprocable dogs or pawls under tension of the powerful 20 spring means quickly and safely locks the collar to the shaft. The provision of the trigger and locking bar mechanism permits mounting the collar in a condition ready to be applied to a shaft, and instantly upon being applied to the shaft releases the locking dogs or pawls so that 25 danger of the collar being thrown from the revolving shaft is avoided.

Having described one preferred embodiment of the invention, I claim:

30 1. A snap-on collar for winder shafts comprising a unitary U-shaped housing having an open throat of a width slightly in excess of the diameter of the winder shaft and of a length that the ends of the throat extend beyond the surface of the shaft as a whole, by means of which the 35 collar may be placed on the shaft while the latter is in motion, and means for automatically locking the collar upon the rotating shaft as the collar is placed upon the shaft.

40 2. A snap-on collar for winder shafts comprising a U-shaped housing having an open throat adapted to be positioned around a rotating shaft, locking means normally positioned within the housing, and means for releasing said locking means into locking engagement with said shaft.

45 3. A snap-on collar for winder shafts comprising a U-shaped housing having an open throat adapted to be positioned around a rotating shaft, locking means normally positioned within the housing, and means automatically operated upon placing the collar coaxial of said shaft for releasing said locking means into locking engagement with said shaft.

50 4. A snap-on collar for winder shafts comprising a U-shaped housing having an open throat, adapted to be positioned around a rotating shaft, a plurality of locking pawls normally positioned within said housing, and means for releasing said pawls from said housing.

55 5. A snap-on collar for winder shafts comprising a U-shaped housing having an open throat adapted to be positioned around a rotating shaft, a plurality of locking pawls normally positioned within said housing, means for releasing said pawls from said housing, and spring means for holding said pawls in tight engagement with said shaft.

6. A snap-on collar for winder shafts comprising a U-shaped housing having an open throat adapted to be positioned around a rotating shaft, locking members normally positioned within said housing, spring means in engagement with said locking members, latch means for holding said locking members within said housing under tension of said spring means, and means for releasing said latch means.

7. A snap-on collar for winder shafts comprising a U-shaped housing having an open throat adapted to be positioned around a rotating shaft, locking members normally positioned within said housing, spring means in engagement with said locking members, latch means for holding said locking members within said housing under tension of said spring means, and means having a part normally lying in said throat for releasing said latch means as the collar is applied to said shaft.

8. A snap-on collar for winder shafts comprising a U-shaped housing having an open throat adapted to be positioned around a rotating shaft, locking members normally positioned within said housing, spring means in engagement with said locking members, latch means for holding said locking members within said housing under tension of said spring means, and trigger means having a part normally lying in said throat for releasing said latch means as the collar is applied to said shaft.

9. A snap-on collar for winder shafts comprising a U-shaped housing having an open throat adapted to be positioned around a rotating shaft, locking members normally positioned within said housing, spring means in engagement with said locking members, latch means for holding said locking members within said housing under tension of said spring means, and lever means fulcrumed to said housing and having a part normally lying in said throat for releasing said latch means as the collar is applied to said shaft.

10. In combination with a rotating shaft of a winder machine, a collar adapted to be mounted on said shaft comprising a housing having an open throat at one side thereof whereby said collar may be applied to said shaft while in motion, a pair of fixed dogs mounted in said housing for engagement with said shaft on one side of the vertical axis thereof, and a plurality of movable dogs adapted for engagement with an opposite side of said shaft.

11. In combination with a rotating shaft of a winder machine, a collar adapted to be mounted on said shaft comprising a housing having an open throat at one side thereof whereby said collar may be applied to said shaft while in motion, a pair of fixed dogs mounted in said housing for engagement with said shaft on one side of the vertical axis thereof, and a plurality of movable dogs adapted for engagement with an opposite side of said shaft, said movable dogs being retroactable into said housing to permit said collar to be applied to and removed from said shaft while in motion.

JACOB F. ALBRIGHT.
